FLASHLIGHT

Joseph G. Bacevius, Bridgeport, Conn., assignor to
Paul G. Garrity, Stamford, Conn.

Filed Jan. 6, 1970, Ser. No. 20,783

Term of patent 14 years

Int. Cl. D26—04

U.S. Cl. D48—24

FIG. 2

FIG. 3

FIG. 4

FIG. 7

FIG. 6

FIG. 8

FIG. 9

FIG. 1 is a side elevation view of a flashlight showing my new design.

FIG. 2 is a top plan view thereof.

FIG. 3 is a bottom plan view thereof.

FIG. 4 is a front elevation view thereof.

FIG. 5 is the rear end view thereof.

FIG. 6 is a side elevation view of a second embodiment of the flashlight of my design.

FIG. 7 is a top plan view thereof.

FIG. 8 is a bottom plan view thereof.

FIG. 9 is a front elevation view thereof.

FIG. 10 is a rear elevation view thereof.

I claim:

The ornamental design for a flashlight, substantially as shown and described.
